UNITED STATES PATENT OFFICE.

AUGUSTIN L. J. QUENEAU, OF SOUTH BETHLEHEM, PENNSYLVANIA.

METHOD OF MAKING AND UTILIZING GAS.

No. 865,727.

Specification of Letters Patent.

Patented Sept. 10, 1907.

Application filed August 4, 1905, Serial No. 272,742. Renewed August 9, 1907. Serial No. 387,832.

To all whom it may concern:

Be it known that I, AUGUSTIN L. J. QUENEAU, a citizen of the Republic of France, residing at South Bethlehem, county of Northampton, State of Pennsylvania, have invented certain new and useful Improvements in Making and Utilizing Gas; and I do hereby declare the following to be a full, clear, and exact description of the invention, such as will enable others skilled in the art to which it appertains to make and use the same.

10 The customary plant for open hearth furnaces, retort furnaces, and like combustion furnaces of the regenerative or recuperative system, comprises, as its main elements, the combustion furnace itself, a gas producer, and a regenerator or recuperator, (either of the checker-work or of the counter current type), wherein the waste heat of the products of combustion is imparted either to the incoming producer gas or to the secondary air employed for its combustion, or to both. To obtain the most economical conditions for the production and 15 ultimate consumption of the fuel, however, not only should the gas current and the secondary air current be thus preheated by the waste products of combustion but also the primary air current *i. e.*, the air delivered into the gas producer for the generation of the 20 gas. This fact has been recognized theoretically and attempts have been made to put it into practical operation, but with only partial success because of inherent difficulties in the expedients proposed for the purpose. To preheat the air intended for the gas producer to any 25 important extent, without further precautions, is not feasible from a practical standpoint, for the reason that gas producers are not constructed to withstand a temperature higher than, say, 400° C. for the injected air. This will be apparent from the following considerations. The temperature of carbon burning to carbon 30 monoxid is 1290° C. If the requisite primary air is preheated to 1000° C., the temperature of combustion will rise to 1985° C. At 1500° C. for the temperature of the primary air, the resulting temperature of combustion to carbon monoxid will rise to 2380° C. It will be readily understood that, with cast iron grates or bush plates, any such temperature, maintained in the ash-pit, would soon result disastrously to the producer, inasmuch as cast iron fuses or melts at, say, 1100° to 1275° 35 C. Moreover, if by any possibility a gas producer capable of withstanding these extraordinary temperatures could be devised, the gas would rapidly lose its high temperature in transit from the producer to the combustion furnace which latter for well understood reasons is usually located at a considerable distance from the producer house; or, if it passed directly into a recuperator, its initial heat would be much too high to be susceptible of effective recuperation. To these disadvantages must be added excessive slagging of the ash-bed, which, of itself, would be sufficient to seriously interfere with the operation of the producer.

My present invention permits the desired recuperation or preheating of the incoming air entering the gas producer, and avoids the disadvantages hereinbefore noted. Its characteristic feature consists in first preheating the air to the desired high degree by waste heat from the products of combustion of the furnace, and absorbing and rendering latent this heat in the producer by the expedient of injecting a proportionate quantity of water into the producer, preferably at the ash-pit. This 60 injection of water, in liquid form, has a two-fold function. It not only renders latent the recuperated heat of the primary air, thereby avoiding its destructive effects upon the producer, but is itself vaporized in so doing and is added to the volume of combustible elements of the final product, its hydrogen being set free and its oxygen uniting with carbon of the charge to form carbon monoxid. This vaporization of the water injected, is obtained wholly at the expense of the recuperated waste heat and without the expense of a 65 separate boiler plant and the outlay required for building and operating the latter.

By injecting the water in liquid form, into the preheated air, and obtaining its vaporization thereby, the gas is greatly enriched in latent calories, thereby preparing it for much more efficient recuperation. This 70 will be apparent from the following considerations; the introduction of steam as such into the producer and thence into the producer charge results in transforming a certain proportion of the sensible heat of the charge 75 into latent heat, according to the reaction

resulting in the absorption, as latent heat, of 28.8 calories. The injection of water at ordinary atmospheric temperatures (say 15° C.) into the preheated air and its 80 subsequent vaporization and passage through the charge results in the absorption of 11.2 calories, a difference of 42.4 calories per molecule of water used, in favor of the use of liquid water. Moreover, the higher the temperature of the incoming primary air, the 85 greater is its capacity for vaporizing the injected water; consequently the richer is the resultant gas, inasmuch as the amount of carbon converted into carbon monoxid by the water vapor in comparison to the carbon converted into carbon monoxid by the air increases with 90 the temperature of the latter, the net result being that the final product of the producer is richer in CO and H, and contains less nitrogen, and therefore has not only a higher fuel value, but being of correspondingly less 95 volume is more economically piped to the distant combustion furnace. Furthermore, the injection of the maximum quantity of water keeps down the temperature of the ash bed below the temperature at which clinkers would otherwise form, thereby serving as a preventive to the formation of clinkers, rather than as a 100 means for breaking them up when formed.

In the accompanying drawings, I have illustrated one form or embodiment of my invention, the illustration chosen showing its application in a system employing a producer of the Taylor type correspondingly modified.

5 Figure 1 represents such a system, partly in section and partly in elevation. Fig. 2 represents, on a larger scale, a sectional view of the lower part of the producer; and Figs. 3 and 4 represent detail views on a still larger scale.

10 Similar letters of reference indicate similar parts throughout the several views.

Referring to the drawings, A indicates the producer, and B the distant regenerative furnace, which, as shown, is of the Siemens or checker-work type familiar 15 to the art, and which need not be further described, except to state that a indicates the combustion chamber; b the secondary air regenerators; c the gas regenerators; d the secondary air inlet; e the gas inlet conduit from the producer; and f, g, the reversing valves.

20 The products of combustion from the regenerators for the gas and secondary air, do not pass directly to the stack, but first traverse an additional regenerator preferably of the counter current type as shown at C. This additional regenerator is intended for preheating the 25 primary air current (i. e. the air to be supplied to the producer) and may conveniently be provided with a serpentine pipe or conduit h heated externally by the products of combustion on their way to the stack D.

E indicates a blower for supplying air to conduit h, 30 and i indicates the continuation of that conduit, leading to the producer.

The arrows in Fig. 1 indicate the direction of the currents, when the reversing valves are in the adjustment shown.

35 As shown more clearly in Figs. 2, 3 and 4, the producer of the Taylor type therein illustrated is modified by me in several particulars. In the first place, instead of introducing the air by the Koerting steam injector as is usual in these producers, I supply it by 40 means of the blower. By this expedient, the supply of air is entirely independent of the supply of water vapor to the producer, as will presently appear, and can be increased, diminished and regulated at will. In the second place, I have provided means for introducing 45 water in liquid form into the producer. Thus, for instance, I surround the bosh plates of the producer with a bustle pipe j, which may conveniently receive its supply from the water jacket k. From this bustle pipe, fine sprays of water escape through suitable apertures, and are directed toward the bosh plates and into the surrounding air chamber. The bustle pipe may also have a series of upward branches l, communicating with a supplemental bustle pipe m, said upward branches and supplemental bustle pipe being likewise 55 perforated for the discharge of fine water sprays. Furthermore, the cast-iron bosh-plates themselves may be provided with coils of wrought iron pipe n, embedded therein during the casting operation, which pipe coils n are connected by spray pipes p with the bustle-pipe 60 j, and which are themselves slotted, as shown, so as to discharge water sprays into the surrounding air chamber and into the ash bed as well. The pipes n, embedded in the bosh plates r, preferably pass back and forth,

in a zig-zag course between the air inlets s of the bosh plates, so as to obtain as uniform a distribution of the 65 water sprays as possible. The air may conveniently be admitted directly into the ash pit or surrounding air chamber through the inlet t.

The operation of the system will be well understood. The products of combustion from the furnace, after 70 traversing the regenerators for the gas and secondary air, pass through the regenerator for the primary air, and thence to the stack, thereby raising the temperature of the primary air current to be supplied to the producer to a temperature which will closely approach the 75 temperature of the waste products themselves. This high temperature of the preheated primary air would raise the temperature of the producer to such an excess that the cast iron bosh plates or grate bars, as the case might be, would be destroyed and the ash bed of the 80 producer fuel would slag to such an extent as to entirely interrupt the operation. The injection of the water sprays, in rendering latent the dangerous excess of temperature, entirely avoids these difficulties, and, in so doing, adds a large quantity of available water gas to 85 the gas current issuing from the producer, besides reducing materially the amount of air which would otherwise be necessary for the efficient operation of the producer, and consequently insuring a richer product and one which can be recuperated to better advantage and 90 piped more economically to the combustion furnace; all as hereinbefore more fully explained.

What I claim is:—

1. The method of making and utilizing gas, which consists in generating producer gas, consuming the gas in a 95 suitable furnace, preheating the air-blast for the producer to a high degree by waste heat from the products of combustion, and simultaneously rendering latent the dangerous excess of temperature of the preheated air-blast, by commingling with it, sprays of water; substantially as described.

2. The method of making and utilizing gas, which consists in generating producer gas, consuming the gas in a suitable furnace, preheating the air-blast for the producer to a high degree by waste heat from the products of combustion, and simultaneously rendering latent the dangerous excess of temperature of the preheated air-blast, by 100 commingling with it, sprays of water, introduced into the ash-pit of the producer; substantially as described.

105 3. The method of making and utilizing gas, which consists in generating producer gas, consuming the gas in a suitable furnace, preheating the air-blast for the producer to a high degree by waste heat from the products of combustion, and simultaneously rendering latent the dangerous excess of temperature of the preheated air-blast, by 110 commingling with it, sprays of water, introduced into the ash-pit of the producer and directed against its heated surfaces; substantially as described.

115 4. The method of making and utilizing gas, which consists in generating producer gas, consuming the gas in a suitable furnace, preheating the air-blast for the producer to a high degree by waste heat from the products of combustion, and simultaneously rendering latent the dangerous excess of temperature of the preheated air-blast, by 120 commingling with it, sprays of water, introduced into the ash-pit of the producer and also into the ash-bed of the producer fuel; substantially as described.

In testimony whereof I affix my signature, in presence of two witnesses.
